DESIGN FOR A HOUSING FOR ELECTRICAL APPARATUS

Edward O. Gaguski, Baltimore, Md., assignor to Bendix Aviation Corporation, New York, N. Y., a corporation of Delaware

Application September 23, 1944, Serial No. 115,429

Term of patent 14 years

(Cl. D26—5)

To all whom it may concern:

Be it known that I, Edward O. Gaguski, a citizen of the United States, residing in Baltimore, Maryland, have invented a new, original, and ornamental Design for Housing for Electrical Apparatus, of which the following is a specification, reference being had to the accompanying drawing, forming a part thereof.

Figure 1 is a view in perspective of the housing for electrical apparatus, viewed obliquely from the front and showing my new design.

Figure 2 is a view in perspective of the housing for electrical apparatus, viewed obliquely from the rear.

The dominant features of my design reside in the portions shown in full lines.

I claim:

The ornamental design for a housing for electrical apparatus, as shown and described.

EDWARD O. GAGUSKI.
